UNITED STATES PATENT OFFICE.

ALBERT W. JACOBS, OF ROCHESTER, NEW YORK, ASSIGNOR TO STAR HEADLIGHT & LANTERN CO., OF ROCHESTER, NEW YORK, A CORPORATION OF NEW YORK.

LANTERN FOR PROJECTION APPARATUS.

1,247,841.

Specification of Letters Patent. Patented Nov. 27, 1917.

Application filed March 17, 1917. Serial No. 155,405.

To all whom it may concern:

Be it known that I, ALBERT W. JACOBS, a citizen of the United States, and resident of Rochester, in the county of Monroe and 5 State of New York, have invented certain new and useful Improvements in Lanterns for Projection Apparatus, of which the following is a specification.

The present invention relates to lanterns 10 for projection apparatus, and an object thereof is to provide a construction which will be inexpensive to manufacture so that the same may be built to be sold to amateurs and others who do not require an expensive apparatus. Another object of this 15 invention is to provide a combined lens tube and hood which are so connected together that both may be simultaneously removed from the lantern casing. A further object is to provide an inexpensive 20 means for admitting air to the lamp casing.

To these and other ends, the invention consists of certain parts and combinations of parts all of which will be hereinafter 25 described, the novel features being pointed out in the appended claims.

In the drawing:

Figure 1 is a view, in side elevation, of a lantern constructed in accordance with the 30 present invention;

Fig. 2 is an enlarged sectional view on the line *a—a*, Fig. 1;

Fig. 3 is a sectional view on the line *b—b*, Fig. 2; and

Fig. 4 is a vertical sectional view through the lens tube and hood showing the connection of the latter to the lamp housing.

The lamp housing or casing is preferably 40 formed by four vertical walls and a top and a bottom wall, 1 indicating the side walls, 2 the front side wall, and 3 the rear wall. The front wall is secured to the side walls 2 in any suitable manner, and these in turn are connected by the top wall 4 and 45 the bottom wall 5, the bottom wall having upwardly turned flanges 6 about the same fitting within the side walls 1 and the front wall 2, said walls being turned inwardly at 7 under the bottom wall 5 to support the latter. The side walls 1 are also bent at 50 their rear edges outwardly at 8 and thence inwardly at 9 to provide a groove 10, an outwardly extending portion 11 being

formed on the inwardly turned portion 9 to strengthen the outer wall of said groove. 55 Within the grooves 10 the rear wall 3 is adapted to slide, said wall having a weight 12 which normally holds the wall or closure 3 in closed position, and also having an inwardly turned flange 13 at its upper end 60 to limit the downward movement of the wall or closure 3.

Any suitable light source may be mounted within the lamp housing, and in order to conduct the heat from the interior of the 65 housing the latter has vent openings at the top and bottom thereof. In this instance, the vent opening at the top is in the form of an annular flange 14 projecting upwardly from the top wall 4 of the housing 70 and having a cap 15 arranged above the same in spaced relation to the flange in order that the heat may pass above the upper end of the flange 14 and thence downwardly around the lower end of the cap. 75 The front wall 2 and the side walls 1 are provided with a number of openings 17 which, on the interior of the housing, may or may not be closed by foraminous material 18. On the exterior of the housing 80 a groove or chamber 19 is provided communicating with said opening 17 and opening at the bottom, said chamber being preferably formed by a sheet metal skirt 20 spaced from the side walls 1 and the front 85 wall 2 below the uppermost portions of said openings 17 and having inwardly turned portions 21 at their upper edges secured to said front wall and side walls.

A feature of this invention is the form 90 and construction of the lens tube and hood which comprises, in this instance, a cylindrical or tube portion 22 and a tapered or frusto-conical portion 23 forming the hood. Preferably these two parts are made of 95 separate pieces of material, the inner end of the tubular portion 22 being bent inwardly at 24 to form a flange or seat for the lens 25, while the hood portion is bent outwardly at 26 and thence about the 100 tubular portion 22 at 27, so that the joint between the hood portion 23 and the tubular portion 22 serves to support the flange or seat 24 of the lens 25. With the object of holding the lens 25 to the seat 24, a holding or retaining ring 28 may be provided 105

which fits tightly the inner wall of the tubular portion 22 and has laterally turned flanges 29 and 30 at opposite ends forming lens seats, the seat 29 coöperating with the 5 lens 25 and the seat 30 coöperating with the lens 31 which is received loosely within the opposite end of the tubular portion 22.

To connect the lens tube and hood to the lantern casing, the latter preferably has an 10 annular flange 32 projecting from the front wall thereof about an opening in said wall, said flange being secured to the wall by providing an inwardly turned portion 33 thereon resting against the wall 2 about the opening 15 and having a portion 34 on the wall bent outwardly over the flange 33. This arrangement provides a support for a lens seat 35 which is rigidly secured to the outwardly turned portion 34 and coöperates with the 20 flat face of the lens 31 when the lens tube 22 is fitted within the sleeve 32. For locking the lens tube 22 within the sleeve 32 the lens tube may carry a pin 36 which is adapted to be passed into a bayonet slot 37 formed 25 in the uppermost portion of the flange. By this arrangement the lens tube 22 and its hood 23 may be readily detached from the flange 32, while at the same time these parts are securely held to the flange by the bayonet joint. As this joint is located at the 30 uppermost part of the flange 32, only one of said joints is necessary as the lower portion of the lens tube abuts the lens seat 35. The lenses 25 and 31 are the usual plano- 35 convex type employed in condensing systems of projection apparatus.

From the foregoing it will be seen that there has been provided a lantern for projection apparatus which is inexpensive to manufacture. The ventilating means is of the simplest form, preventing the escape of light. The lamp casing is closed by a simple slide in its rear wall, and the condensing system is detachably supported on the front 40 wall. The supporting means is in the form of a flange which is secured to the lamp housing or casing in such a manner that the securing means acts as a support for one of the lenses of the lens tube, and at the same 45 time permits a single bayonet joint to be employed for securing the lens tube in position. The lens tube carries the hood which forms a continuation of the tube and at the same time acts to strengthen or support 50 the seat for that lens of the condensing system which is situated at the juncture of the lens tube and the hood.

What I claim as my invention and desire to secure by Letters Patent is:

1. In combination with a lamp housing 60 having a projecting cylindrical flange formed with a lens seat, a combined lens tube and hood detachably fitting within said flange, the lens tube being cylindrical and the hood tapering from said tube and forming an unbroken continuation of the latter, a lens seat at the junction of the hood and the tube, a lens resting against the last named seat, a lens resting against the lens seat of the flange, and a holding ring fitting 65 in said lens tube and engaging both lenses. 70

2. A lantern for projection apparatus comprising a lamp casing, a circular flange projecting from said casing, a lens seat in 75 said flange, a condensing lens abutting said seat, a tube fitting in and detachably interlocking with said flange, and a lens seat carried by said tube to engage the lens on the side thereof opposite the side engaged by the lens seat of the flange. 80

3. A lantern for projection apparatus comprising a lamp casing, a tube projecting from said casing and having one end turned inwardly to provide a seat for engaging one 85 face of the lens, a lens holding ring fitting in said tube and having a seat for engaging the opposite face of a lens, and a tapered hood connected to said tube and bent to cooperate with the tube flange to strengthen the latter. 90

4. A lantern for projection apparatus having a light-proof top wall provided with a vent opening, a bottom wall, light-proof sheet metal side walls having their upper edges secured to the top wall and their lower edges secured to the bottom wall, said side walls having openings therein, a lens tube projecting from one of the side walls above said openings, and a horizontally-extending light-skirt closed at its top and sides and 100 depending from said side walls over the openings to form a chamber open at its bottom. 105

5. A lantern for projection apparatus comprising a housing or casing with an 105 opening, a flange member having an inwardly turned portion abutting the housing about the opening, the metal of the housing about the opening being turned outwardly to overlap the inwardly turned portion on the flange member, and a lens tube detachably fitted in said flange member. 110

ALBERT W. JACOBS.
